CLAIM

The ornamental design for an alien inflatable costume, as shown and described.

DESCRIPTION

FIG. 1 is a perspective view of an alien inflatable costume showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the alien inflatable costume shown in use and with environment.

The broken lines in the drawings depict portions of the alien inflatable costume that form no part of the claimed design.
